UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

AERIAL SYSTEM.

Application filed October 5, 1923. Serial No. 666,703.

My invention relates to aerial systems for the radiation of high-frequency energy.

Broadly speaking, my invention has for one of its objects the construction of an aerial system which shall have a maximum radiation resistance and which shall operate at the maximum frequency obtainable with a given capacity value.

Another object of my invention is to provide an aerial system which shall be suitable for simultaneous operation at two different frequencies and which shall minimize the swinging of signals due to change of frequency on short wave lengths.

15 A further object is to provide a system which shall be free from harmonics and which shall be readily operable at various frequencies.

More specifically, an object of my invention 20 is to provide a radiating system consisting of an aerial and counterpoise connected by a minimum length of conductor, in order that the inductance in the radiating circuit may be as small as possible for a given height and 25 that the ratio between the radiation resistance and the total resistance of the system may be as large as possible.

It is an object, also, to provide an aerial and counterpoise radiating system of such dimensions as to radiate at some chosen wave 30 length, which system shall also be of such construction as to permit of the aerial and counterpoise together serving as the elevated capacity element of a second radiating system 35 whose other capacity element is the ground.

It is further an object of my invention to so 40 construct and energize an aerial and counterpoise system that it is possible to send two signals on two different wave lengths simultaneously.

It is a still further object of my invention to so connect the aerial and counterpoise system to an oscillation generator as to minimize the effect of changing constants of the aerial 45 and counterpoise system in changing the frequencies of radiated signals.

In practising my invention, I provide an aerial elevated above the ground, a counterpoise placed between the aerial and the ground, and a connecting wire, between aerial and counterpoise, which is of minimum length and which may even be a straight con-

ductor. I also provide a source of high-frequency energy which may be a triode oscillator, an arc or other suitable generator. I 55 connect the source of high-frequency energy to the aerial circuit at a point other than the electrical midpoint, as will later be explained. I may also connect a conductor between the electrical midpoint and the ground, which 60 conductor may contain an inductance, coupled to a second source of high-frequency energy.

Other objects and structural details of my invention will be apparent from the following 65 description and claims, when read in connection with the accompanying drawing, wherein

Figure 1 is a diagrammatic view of circuits and apparatus embodying my invention.

Fig. 2 is a similar view of a modification. 70

Fig. 3 is a similar view of a second modification adapted for the radiation of two frequencies.

In the system of Fig. 1, I provide an elevated capacity or aerial 1 and a counterpoise 2 that are connected together by a conductor 3. The constants of the aerial and counterpoise may preferably be chosen of such value that the electrical midpoint of the system, when in oscillation, will lie upon the conductor 3 at point 4. A ground wire 5 may be connected to point 4 and to ground 6, if desired, or may be omitted, without hindrance to the oscillation of the system composed of aerial 1, counterpoise 2 and conductor 3. 80

A source of high-frequency energy 7 may be of any suitable type, such as a thermionic triode generator, an arc, a spark, or other source. The oscillation generator 7 is connected to the aerial radiation system composed of aerial 1, counterpoise 2 and lead wire 3 by a conductor 8 and condenser 9. Connection is made to a point 11 on conductor 3, this point being so chosen that it is not the electrical midpoint of the oscillating 85 system.

Fig. 2 shows my invention with a minor modification. It may be desired to transmit alternatively at more than one wave length from an aerial and counterpoise system. This can be done by constructing aerial and counterpoise with such constants that one of the desired frequencies will be obtained by the use of a straight lead wire between aerial 100 and counterpoise.

and counterpoise. The other frequency may then be obtained by introducing into the lead wire either additional inductance or additional series capacity according as the other frequency desired is lower or higher than the first chosen frequency.

This construction is shown in Fig. 2 in which structures corresponding to those of Fig. 1 are indicated by similar reference characters. In addition, an inductance 12 and a short-circuiting switch 13 are shown.

Fig. 3 shows diagrammatically the structure of my invention required for transmitting two signals at different wave lengths simultaneously. In Fig. 3, structures identical with those of Figs. 1 and 2 are indicated by similar reference numerals. In Fig. 3, ground lead 5, which is indicated as alternative in Figs. 1 and 2, is necessarily present. In this ground lead 5 is inserted an inductance 14 which is in inductive relation to coil 15 of the secondary of oscillation generator 16.

It is well known in the art that maximum efficiency is obtained in an antenna system when the radiation resistance is a maximum portion of the total high-frequency resistance of the aerial system. It is also well known that a maximum radiation resistance in any antenna system is favored by a minimum inductance in the radiating circuit for a given frequency; that is, an aerial system will radiate best when it has no inductance coil in the lead connecting aerial and counterpoise and when the inductance of the connecting lead itself is a minimum. Under these conditions, the aerial, when energized, is said to oscillate at its fundamental frequency. Conversely, the maximum radiation resistance is obtained in a given aerial when it oscillates at its fundamental frequency.

It is well known in the art that, in an antenna system consisting of an aerial and counterpoise, it is possible to find a point in the circuit which remains at zero potential with respect to the ground even though the antenna system be energized into oscillation. This point is a potential node with respect to ground and likewise a current loop, the current node and potential loop occurring at the free ends of the oscillating system. This point of constant potential or potential node may be called the electrical midpoint of the oscillating system. One of its characteristics is that it may be connected to ground by a conductor without current traversing the grounding conductor.

It is further possible to connect a second source of high-frequency energy to the electrical midpoint of such an oscillating system and cause electrical oscillations to take place between the antenna system as a whole and the ground without interfering with the oscillations of the antenna and counterpoise themselves, thereby obtaining duplex operation.

In operation, the radiating system composed of aerial 1, counterpoise 2 and lead 3 will have a definite natural period of oscillation. The oscillation generator 7, which is a source of high-frequency energy, is adjusted to the same frequency as the normal period of the radiation circuit by means which are well known to those skilled in the art. The condenser 9 is then adjusted to such value as to give adequate transfer of energy from generator to radiator without obtaining coupling so close as to produce undesirable reaction between generator and radiator circuits. Under these conditions, high-frequency current oscillations will build up in the radiation system to a value determined by the resistance of the radiation circuit and the energy input.

While in operation, the electrical midpoint 4 of the oscillating system may be connected to ground by lead 5 without influencing the oscillation of the system. The presence of lead 5, however, drains off any atmospheric or other undesired energy.

When it is desired to transmit at a different frequency, the change in constants of the radiating system may be produced by the introduction of additional impedance, which may be an inductance 12, shown in Fig. 2, or may be a condenser. The additional impedance represented by inductance coil 12 may be brought into and out of the circuit by means of a short-circuiting switch as shown.

Aerial 1 and counterpoise 2 may be considered together as an ordinary elevated capacity and connected to a ground at their electrical midpoint, under which condition they will function together as an antenna. Since a ground connection may be made through the electrical midpoint of the antenna and counterpoise system without effecting its oscillation as a whole, it is obvious that it is possible to connect it with the ground by means of connection 5, and an additional inductance coil 14, which will then serve as a means for the transfer of energy from another high-frequency generator. Under these conditions, the aerial and counterpoise structure is made to serve together as one capacity element of the oscillator system of which the other capacity element is the ground. The generator 7 then transmits signaling energy to the aerial and counterpoise at one frequency, and generator 16 transmits energy through inductance coil 14 to the same system and causes it to oscillate at the same time at a different frequency for the transmission of a different signal.

The use of the oscillation driver 7 loosely coupled to the radiation circuit composed of the aerial 1, counterpoise 2 and lead 3 allows the radio-frequency generator 7 to oscillate at a frequency, which, while adjusted to the same value as that of the radiating circuit, is set by its own constants independently of

the constants of the radiating circuit. This means that energy is supplied for radiation at a constant frequency which is not affected by minor changes in the constants of the radiating circuit of the kind produced by swaying of the antenna or the conductor leading thereto in the wind or by movement of objects below or between aerial and counterpoise which changes the effective capacity between them.

10 This construction is of particular advantage in signaling with short-wave undamped signals. These signals are received by methods which require heterodyning by a local oscillator circuit at the receiving station 15 to produce a beat note, which is received by the operator's ears, its frequency and pitch depending upon the relationship between the incoming and the local frequencies. A minor change in the radiating frequency at short 20 waves is sufficient to transfer the beat note out of the range of audibility, resulting in the loss of signals when even a minor change of constants of the radiating circuits takes place. My system, by virtue of the loose-coupled 25 connection between radiator and generator, keeps a fixed frequency and thereby avoids this difficulty.

Furthermore, the fact that the oscillation generator is loosely coupled to the radiating 30 circuit permits of the transfer of energy only at the frequency to which both circuits are tuned, thereby largely avoiding the radiation of harmonics.

Also, the fact that it is possible to connect 35 the aerial, counterpoise, and lead systems to ground at an electrical midpoint, without influencing the oscillation of the system, enables the system, as a whole, to be used as an aerial which, in turn, permits the radiation of the 40 second set of signals supplied from another energy source.

While I have shown only three embodiments of my invention in the accompanying drawing, it is capable of other changes and 45 modifications without departing from the spirit thereof, and I desire, therefore, that

only such limitations shall be placed thereon as are indicated in the prior art or in the appended claims.

I claim as my invention:

50 1. An antenna system comprising an aerial, a counterpoise, a conductor of minimum inductance therebetween, an oscillation generator at a distance greater than the sphere of inductive influence, and a single-conductor 55 link circuit therebetween.

2. An antenna system comprising an aerial, a counterpoise, a conductor therebetween of minimum length, an oscillation generator at a distance greater than its sphere of inductive influence, and a single-conductor link 60 circuit therebetween.

3. An antenna system comprising an aerial, a counterpoise, a conductor therebetween of minimum length, an oscillation generator at 65 a distance greater than its sphere of inductive influence, and a single-conductor link circuit therebetween having impedance means therein.

4. A radiation system for high-frequency 70 energy comprising an aerial, a counterpoise and a linear conductor therebetween, an oscillation generator at a distance greater than its sphere of inductive influence therefrom, a single-conductor link circuit therebetween, 75 a ground connection to a voltage-node point on said linear conductor, and a radio-frequency supply associated therewith.

5. A system for the radiation of high-frequency 80 energy at a chosen frequency comprising an aerial, a counterpoise, and a conductor therebetween of minimum length, the areas and separation of said aerial and counterpoise being such that the desired resonant 85 frequency is obtained with said conductor therebetween of minimum length, an oscillation generator, and a link circuit therebetween having a capacitance between sections thereof.

In testimony whereof, I hereunto subscribe 90 my name this 2nd day of October, 1923.

FRANK CONRAD.
